UNITED STATES PATENT OFFICE

ELLSWORTH GRAY, OF HOUSTON, TEXAS, ASSIGNOR TO GRAY TOOL COMPANY, OF
HOUSTON, TEXAS, A CORPORATION OF TEXAS

OVERSHOT FISHING TOOL

Application filed September 19, 1927. Serial No. 220,406.

My invention relates to improvements in fishing tools for use in well drilling to telescope over and engage pieces of broken pipe, drill stem and similar parts that have been lost in the well.

In gripping and withdrawing objects, such as pipe, drill stem and similar parts in a well, it is often found that the object is stuck in the well and cannot be easily withdrawn. In such case, if the fishing tool has obtained a firm grip upon the object to be withdrawn, it becomes necessary that the engagement between the tool and the object be released so that the tool may be withdrawn and other operations entered into with the idea of removing the junk from the well.

It is an object of my invention to provide a fishing tool of the character noted which can be readily released from the object after engagement has been made therewith, and in which the gripping means is made strong and substantial and not liable to fail in use.

It is also an object to provide means to cause a positive and firm engagement between the fishing tool and the object which is engaged.

It is another object to provide means to close off the space between the walls of the fishing tool and the pipe which is engaged by the tool so that flushing fluid may be pumped downwardly through the pipe or drill stem upon which the tool is mounted and the return of liquid inside the tool may be prevented. It is desired to form a substantial seal between the body of the tool and the object which is engaged so that there may be no passage of liquid between the tool and said object.

It is a further object to provide a type of shoe on said tool which will enable the operator to more readily engage the object which is to be removed.

Referring to the drawing herewith, Fig. 1 is a central vertical section through a fishing tool embodying my invention. Fig. 2 is a transverse section taken on the plane 2-2 of Fig. 1 and in the direction of the arrows. Fig. 3 is a bottom plan view of the device shown in Fig. 1 illustrating the formation 50 of the shoe attached to the device.

The body 1 of my device is a cylindrical tubular member threaded at 2 at its upper end for connection with a collar 3 by means of which it may be engaged with the tube or drill stem 4, said drill stem extending upwardly to the surface for operation. The lower end of the body 1 is threaded at 5 for connection with a shoe 6 for engagement with the pipe or drill stem which is to be withdrawn from the well.

The shoe 6 is cylindrical on its outer surface and has an upper shank 7 having a tapered thread thereon for engagement with the lower end of the body 1. Below the threaded shank 7 there is an upwardly tapered area 8 which is adapted to seat against the lower end of the body 1 and form a firm supporting engagement between the two parts tending to prevent any movement of the shoe relative to the body during the use of the tool. The lower end of the shoe has its inner surface flared outwardly at 9 and its lower end has a sharp bevel 10, thus enabling the tool to better engage over the upper end of a pipe in the well. In addition to the flaring inner surface of the shoe I have formed a notch or recess 11 in said shoe, one side 12 of which is curved. The other side 13 may be vertical, as illustrated, or also slightly beveled or curved. This recess in the wall of the shoe is formed at only one place on its lower side and therefore prevents the shoe from engaging within the upper end of the broken pipe. The notch will, however, when the tool is rotated enable the operator to better telescope the shoe over the upper end of the broken pipe in the well.

The body 1 of the tool has on its inner surface a plurality of gripping dogs 14. I have shown four of these dogs, as will be apparent from Fig. 2. Each dog is formed of an arcuate plate, the lower side of which is adapted to fit upon a shoulder 15 on the inner wall of the body 1. Above the shoulder is a recess or enlargement within the body, shown at 16, within which the dogs may be moved. One side of each dog is shown as formed parallel with the axis of the body. This is indicated at 17 in dotted lines in Fig. 1. The other side or edge 18 is inclined from its lower edge 100

upwardly, making the dog smaller at its upper end than at its lower end. As will be noted from Fig. 2, the inclined side of the dog is also beveled inwardly. This will be seen at 19 in Fig. 2. A sharp forward edge 20 is thus formed on the dog which is in the nature of a thread or cutting face so that when the tool is rotated in a right-hand direction, this sharp forward edge at the upper end will engage with the object which is gripped and tend to cut into the object so as to gradually throw the dogs outwardly as they rotate.

Each of the dogs is secured in position within the recess by screws 21 adjacent the lower end, said screws extending through openings in the walls of the body, the heads of the screws fitting within an enlarged recess 22, thus allowing the free play of the screws in said openings to allow movement of the dogs in an obvious manner. Adjacent the upper ends of the dogs I provide pins 23 which project outwardly from the surface of the dogs and serve to retain a resilient member 24 beneath said pins in position on said dogs. The inner wall of the recess 16 is provided with small recesses 25 to receive the ends of the pins 23, as will be obvious. The resilient member 24 is preferably a rubber band of strong construction which tends to hold the upper ends of the dogs inwardly in the position shown in Fig. 1. While I have shown the rubber band, it is to be understood that any resilient member may be substituted for the band, the purpose being to hold the upper ends of the dogs resiliently toward the object which is to be engaged.

Above the gripping members I have provided a packer or seal member to engage with the object which is to be removed from the well and form a tight closure between the body and said object. In the drawing I have shown a broken pipe 26 within the fishing tool and it is to be understood that this pipe has been broken off within the well and the tool has been telescoped over the upper end thereof. The tool is pushed downwardly over the broken pipe until the dogs 14 engage beneath the collar 27 upon the pipe. This collar may be an ordinary coupling or a tool joint or other similar means of connecting the pipe sections in the well. The seal member indicated at 28 is placed above the gripping dogs a slight distance so that the said seal will contact with the coupling 27 and form a tight closure therewith. The seal member 28 comprises a ring or sleeve of rubber or similar flexible composition. The said sleeve is curved inwardly between its ends so as to form a concave outer face, the inner face being convex and adapted to contact with the coupling. At each end of the sleeve 28 the inner diameter thereof is slightly reduced to receive a metal ring 29, acting to reinforce the packing sleeve and to assist in securing the

said sleeve in position. The inner wall of the body is recessed to receive the sleeve and the ring and, as will be noted in Fig. 1, the inner face of the ring 29 is adapted to come approximately flush with the inner wall of the body. Set screws 30 are extended through the wall of the body to connect with the upper and lower ends of the packing sleeve and hold the same against longitudinal movement. The upper end of the packing sleeve is adapted to contact with the lower end of the coupling member 3, thus assisting in holding the packer in position.

In the operation of my device, the parts will be assembled as shown in Fig. 1 and the tool will be introduced into the well at the lower end of a pipe or drill stem 4 until the broken pipe has been reached. It is usual that the broken pipe stands at an angle in the well leaning against one wall of the well so that it is difficult to engage the shoe of the fishing tool over the upper end of the broken pipe. By forming the notch or recess 11 in the lower end of the pipe at one point around the circumference thereof, I avoid engaging the body of the shoe deeply within the upper end of the broken pipe, but sufficient engagement may be made so that when the fishing tool is rotated, carrying the lower edge of the shoe 6 around against the upper end of the broken pipe, the edge of the shoe will engage the pipe and carry it slightly away from the wall of the well so that the tool will telescope over the upper end of the pipe. I have found that the notch or recess formed in the manner shown at 11 will effectively engage the broken pipe even when the said pipe is placed in an awkward position within the well.

When the tool is engaged over the pipe and is forced downwardly, the upper ends of the dogs 14 will engage below the lower shoulder on the collar 27 of the pipe. The resilient member 24 will assure that the dogs firmly grip and hold the pipe. An upward movement is then exerted upon the broken pipe to remove it. If it is found to be firmly lodged and will not move, the flushing fluid may be pumped downwardly through the drill stem 4 and cause it to pass upwardly around the outer side of the broken pipe 26 and tend to wash the material away from the outer side thereof, so that it may be released from the well. I am enabled to thus wash away the material outside of the broken pipe, due to the packing sleeve 28. This sleeve, when fixed firmly in its seat within the body 1, has an air chamber shown at 31 between the wall of the sleeve and the recess in which it is seated. There is a natural resiliency of the sleeve bowing it inwardly between its ends against the wall of the coupling 27. It is found also that the air chamber 31 formed behind the wall of the sleeve also assists in holding the sleeve firmly against the collar. It has been found that heavy pump pressure is en-

tirely cut off by the using of a seal of this nature, thus enabling the operator to wash the material away from around the broken pipe.

If it is eventually found to be impossible to pull the broken pipe from the well even after it has been washed, the tool may be released by a rotation thereof in a right-hand direction. It will be seen that the upper ends of the dogs 14 bear against the lower shoulder of the collar. The forward edges of the dogs are sharpened off so that they will engage within the metal of the collar and tend to cut a thread or sliver from the lower edge of the collar. This, because of the beveled sides of the dogs, will tend to force the dogs outwardly, crowding them from beneath the collar into the recess 16 against the action of the resilient band 24. This will enable the dogs to slip by the lower edge of the collar 27 so that the device may be pulled upwardly free of the broken pipe to the surface.

The principal advantages of my device lie in the fact that it is simple and strong in construction and not liable to fail in use and to its positive action within the well. It is easily engaged with the broken pipe and again easily released, and the sealing sleeve 28 is not liable to be torn in use and furnishes a strong and stable packing means capable of withstanding comparatively high pressures.

Having thus described my device, what I claim as new is:

1. A fishing tool comprising a tubular body having a dog-receiving recess on its inner side, arcuate dogs in the said recess, means retaining the lower ends of said dogs loosely in said recess, means to hold the upper ends of said dogs resiliently inwardly, means on the forward edges of said dogs beveled to engage the work and cut into the same to force said dogs outwardly upon rotation with respect to the work.

2. A fishing tool including a tubular body, arcuate dogs mounted on the inner face thereof, means to support said dogs with their upper ends inclined inwardly, said dogs being tapered upwardly and beveled inwardly, a forward edge on each dog to cut into the surface being gripped, and cause release of the dogs on rotation of said body.

3. A fishing tool including a tubular body, arcuate dogs mounted on the inner face thereof, and means to support said dogs with their upper ends inclined inwardly, said tool being adapted for rotation in a clockwise direction, forward edges on said dogs beveled inwardly to form work engaging portions adapted to force said dogs outwardly when said tool is rotated.

4. A fishing tool including a tubular body, arcuate dogs mounted on the inner face of said body, means to retain said dogs loosely on said body, a resilient member engaging said jaws to hold the upper ends thereof inwardly, means to hold said resilient member

on said dogs, and an inwardly-bowed packing sleeve in said body above said dogs, adapted by its own resiliency to make a fluid tight contact with the work.

5. A fishing tool including a tubular body, pipe engaging dogs on the inner side of said body, a packing sleeve of compressible material above said dogs, said sleeve being mounted upon said body and normally constructed in a form bowed inwardly between its ends to contact with the said pipe.

6. A fishing tool including a tubular body, pipe engaging dogs on the inner side of said body, a packing sleeve of compressible material above said dogs, said sleeve being mounted upon said body with its ends fixed and the body thereof normally bowed inwardly between its ends to contact with the said pipe, the ends of said sleeve being secured to said body to form an air pocket between said body and said sleeve in the manner stated.

7. In a fishing tool, a tubular body, a recess therein, a tubular packing sleeve in said recess, said sleeve having its walls constricted inwardly between its ends to form an air pocket between said sleeve and said body, and means to hold the ends of said sleeve tightly in said recess.

8. In a fishing tool, a body member, a set of fish-engaging dogs mounted on said body whereby they will move longitudinally therewith, an air cushion packer also mounted on said body above said dogs and adapted to normally close the area between said body and the fish.

9. In a fishing tool, a body member, a shoulder on said body, a set of fish-engaging dogs mounted to abut said shoulder, whereby they will move longitudinally therewith, an air cushion packer also mounted on said body above said dogs and adapted to normally close the area between said body and the fish.

In testimony whereof I hereunto affix my signature this 14th day of September, A. D. 1927.

ELLSWORTH GRAY.
